UNITED STATES PATENT OFFICE.

JOSEPH S. WISHART, OF BROOKLYN, NEW YORK, ASSIGNOR TO WILLIAM JAMES HOGG & SON, OF WORCESTER, MASSACHUSETTS.

DESIGN FOR CARPET.

SPECIFICATION forming part of Design No. 27,449, dated July 27, 1897.

Application filed February 10, 1897. Serial No. 622,861. Term of patent 3½ years.

To all whom it may concern:

Be it known that I, JOSEPH S. WISHART, a citizen of the United States, residing at Brooklyn, in the county of Kings and State of New York, have invented and produced a new and original Design for Carpets, of which the following is a specification.

My invention relates to a design to be worked into or upon carpeting or similar fabrics; and I do hereby declare that the drawing accompanying this specification gives and conveys to any one skilled in the art of carpet-weaving a clear understanding of the same that is sufficient to enable such persons to use my invention.

The said drawing is a face view of a carpet embodying my new design.

The drawing illustrates a body and a border.

The body A consists of a substantially uniform groundwork, upon which are arranged leafy scrolls from which depend festoons of conventional flower and leaf forms.

The border B is formed of festoons of con-

ventional flower and leaf forms similar to those in the body and depending from leafy scrollwork which is so arranged as to form large oblique figures having centers formed by small overlapping conventional flower forms. The outer edge is characterized by curving leafy sprays.

The colors employed for the different portions of this design may be varied to suit the convenience or taste of the manufacturer.

What I claim, and desire to secure by Letters Patent, is—

1. In a design for carpeting, the body A, substantially as shown.
2. In a design for carpeting, the border B, substantially as shown.
3. The design for carpets, consisting of the body A and the border B, substantially as shown.
